UNITED STATES PATENT OFFICE.

WALTER FOWLER, OF LONDON, ENGLAND.

GRAVITY-FEED DEVICE FOR BOILER FEED-WATER.

1,280,435.

Specification of Letters Patent.

Patented Oct. 1, 1918.

Application filed October 4, 1916. Serial No. 123,782.

To all whom it may concern:

Be it known that I, WALTER FOWLER, a subject of the King of England, residing in London, England, have invented certain new and useful Improvements in Gravity-Feed Devices for Boiler Feed-Water, of which the following is a specification.

This invention consists of improvements in or relating to gravity-feed devices for boiler feed-water and is applicable to such devices of the known duplex type that comprise in combination two float-chambers to be placed above the boiler water-level, a float in each chamber, a rocking beam or equivalent connection between the floats, a source of feed-water delivering under a head through non-return influx valves to the underside of each float, and a delivery conduit which delivers the feed-water through non-return delivery valves from the said underside to the boiler. According to this invention a reciprocating steam valve of the sliding piston type and suitable passages are used in an apparatus of the aforesaid duplex type to effect equilibration and exhaust from the upper side of each of the floats in turn, and preferably the controlling valve operatively connected to the floats and acting to shift the said reciprocating valve as each float rises in its own chamber is likewise of the sliding piston type.

The floats can be pistons fitting or approximately fitting the float-chambers which are cylindrical.

It is an important feature of the present invention that the apparatus is so arranged in relation to the highest working level of water in the boiler that it will stop and re-start itself automatically as required; the manner in which this may be effected will be hereinafter fully explained.

In a preferred construction the rocking beam and its connections to the floats are inclosed in a two-part steam-tight chamber so as to render unnecessary any glands or packing for the rods connecting the floats to the rocking beam; the friction to be overcome in operating the device is thereby considerably reduced. The rocking beam is mounted on a rotary plug device in the partition between the two parts of the chamber, and this plug permits the oscillation of the beam but prevents communication between the two parts of the chamber.

A pointer may be connected to the spindle

on which the rocking beam rocks, the pointer being situated outside the chamber so that its movement shows when the beam itself is moving; the steam-operated valve above-mentioned may be operatively connected to a handle situated outside the casting so that the valve can be shifted by hand if so desired.

In the accompanying drawings—

Figure 1 is a diagrammatic representation of a complete gravity-feed installation;

Fig. 2 is a section on the line 2—2 of Fig. 4, showing a preferred construction according to this invention;

Fig. 3 is a section on the line 3—3 of Fig. 4;

Fig. 4 is a section on the line 4—4 of Fig. 2, and

Fig. 5 is a section of Fig. 2 and illustrates a part of Fig. 4 on a plane of section a little farther from the observer than is the plane of section in Fig. 4.

Like reference characters denote like parts throughout the drawings.

The invention will first be described with reference to Fig. 1. A is a tank from which feed-water is supplied to a boiler B. The device by which this is effected comprises two float-chambers C C¹ containing floats D D¹ respectively. The floats are connected by rods E E¹ to a rocking beam F mounted on bearings in the middle of its length so that it can oscillate as the floats rise and fall alternately. The beam F is connected to a piston-valve G so as to reciprocate it when the beam is rocked, and this pilot valve G is contained in a casing G¹ which is connected at H H¹ to the steam space of the boiler B and at J to atmosphere for exhaust. The chamber G¹ is further provided with passages K K¹ which communicate with the two ends of a valve chamber L¹ containing a reciprocating piston-valve L or the main valve; this chamber L¹ also has connections L² L³ with the steam space of the boiler B, L⁴ with atmosphere for exhaust, and L⁵ L⁶ to the upper ends of the float-chambers C C¹ respectively.

The valves G and L are so shaped and their steam passages so disposed as to operate in the manner hereinafter described.

The tank A is connected by a pipe A¹ having in it a stop-valve A² with a casing A³; this casing A³ contains two non-return valves through which water can be supplied from A¹ to either of the float-chambers C C¹, and

a further pair of non-return valves by which water can be delivered from either of the chambers C C¹ through a pipe A⁴ to the boiler. A stop-valve A⁵ is provided on the 5 pipe A⁴ near the boiler.

The operation of the device will now be described starting with the parts described in the position shown in Fig. 1. The float-chamber C¹ is full of water and the valve 10 L is at the left-hand end of its travel thereby admitting steam from the boiler through the pipe L⁶ to the upper part of the chamber C¹ above the float D¹. The upper part of the chamber C is open through the 15 pipe L⁵ to the exhaust L⁴ abovementioned. The water in the chamber C¹ and pipe A⁴ is in equilibrium as regards the steam pressure in the boiler, and it can therefore flow freely into the boiler under the influence of gravity 20 due to the float-chamber being situated above the water-level in the boiler. The upper part of the other chamber C is open to atmosphere and water therefore flows in from the tank A, through A¹, A², A³, to the bottom of the chamber C, so that this chamber 25 fills lifting its float and rocking the beam F. The movement of the beam F carries the pilot valve G toward the right. As it travels in this direction it first opens the steam inlet H and finally opens the passage K so that steam can pass from the boiler into the 30 left-hand end of the cylinder L¹ containing the main valve L. At the same time the passage K¹ has been shut off from the steam pipe H¹, and later opened to the exhaust by the movement of the valve G, so that the 35 right-hand end of the valve chamber L¹ is now open to exhaust. The valve L is therefore forced rapidly across to the right-hand 40 end of its travel. This movement puts the passage L⁶ in communication with atmosphere through L⁴, and provides a direct communication for steam from L² through L⁵ to the upper end of the float-chamber C. The 45 parts are therefore now in a position in which the chamber C is filled with water which is now subjected at its upper side to the steam pressure of the boiler, and the chamber C¹ is emptied with the upper part 50 of it open to atmosphere. This was the condition obtaining at the commencement of the above-described operation and the water in the chamber C flows down into the boiler thus emptying the chamber C and allowing 55 the filling of the chamber C¹. This complete cycle of emptying both chambers C C¹ into the boiler is repeated indefinitely. The rate of working of the device is controlled by means of the valve A² which determines the 60 rate of the flow of water from the tank A into the chambers C C¹, and therefore the speed at which the stroke of the floats is made.

A preferred construction of the floats and 65 their associated valves is shown in Figs. 2, 3

and 4. In order to obviate the necessity of providing stuffing-boxes or glands for the rods E E¹ where they pass out of the chambers C C¹ respectively, the rocking lever F with these rods is inclosed in a two-part 70 steam-tight chamber F² having a partition F³ in the middle. This construction considerably reduces the friction which has to be overcome by the movement of the floats and thereby renders the operation of the device 75 more satisfactory. The beam F is mounted in a cylindrical plug member F⁴ which can turn in a seating F⁵ formed in the partition F³. The beam F is therefore free to move in the chamber F² but communication is effectually prevented between the two parts which are open respectively to the upper parts of the chambers C C¹. The floats D D¹ are cylindrical pistons fitting or nearly fitting the float-chambers which are of the 80 same shape. Guide-rods D² are provided in each of the float-chambers for the floats.

The construction of the controlling and steam-operated valves with their steam connections is shown in Figs. 3 and 4. The 90 rocking beam F is provided with a spindle F⁶ carrying at one end an arm F⁷ by which the valve G is reciprocated. At the other end this spindle carries a pointer F⁸ outside the chamber F², to constitute an indicator 95 showing when the valve is in motion.

The steam-operated valve L is provided as shown in Figs. 3 and 4 with means for operating it by hand if desired comprising a spindle M having a handle M¹ at its outer end and an arm M² at its inner end engaging the valve. Suitable packing is provided for the spindles M and F⁶ to prevent any leakage of steam.

The steam ports and passages are indicated by the same reference letters as are used in Fig. 1 for the corresponding passages. The steam from the boiler enters the casing for the valves at N and enters the chamber of the valve G by both of the ports H and H¹. For convenience both valves are shown in their mid-position. The steam for operating the valve L passes from the chamber of the valve G by either of the passages K K¹ shown most clearly in Fig. 3 and also 105 indicated in Fig. 4. The equilibrating steam passes from the inlet N to the space N¹ and then by either of the passages L² L³ according to which float-chamber is to be supplied. The steam passes around the valve 110 L and out through L⁵ and L⁶ into the chambers containing the rocking beam and connecting links E E¹, each chamber being in communication with one of the float-chambers. The exhaust of the steam takes place 120 through J and L⁴ as was described with reference to Fig. 1.

The box A³ is provided with two pairs of non-return valves as shown most clearly in Figs. 2 and 4. The water from the supply- 130

tank A passes by way of the pipe A¹ to the space A⁶ and thence passes either of the valves P P¹ into the space P² or P³ according to which of the float-chambers is to be filled. When the float-chambers are being emptied, the water passes downward from them into the space P² or P³ and thence through the valves P⁴ or P⁵ into the space P⁶ from which it is delivered by the pipe A⁴ into the boiler.

The operation of the preferred construction is exactly the same as that described with reference to Fig. 1 and the description therefore need not be repeated.

In order that the apparatus shall stop and re-start automatically when the water in the boiler rises to or falls away from its highest working level, the float-chambers C C¹ must be placed at such a level in relation to the boiler that the bottoms of the float-chambers are a little below the said highest working-level. This will insure, so long as the water in the boiler is at or near the highest working level, that it will be at the same level in the float-chambers also; these latter therefore will not clear themselves of water in these circumstances and therefore the floats will not descend far enough to produce actuation of the valve G. The apparatus therefore automatically stops so that the boiler cannot be over-supplied with feed. As soon as the level of the boiler water falls from its highest, the level of the water in the float-chambers will fall also, permitting one or other of the floats to complete its working stroke, whereupon it will once again operate the valve G and the apparatus will resume normal working.

To prevent the water from the tank A from flowing through the float-chambers when the apparatus is stopped, the ports in the chamber F² for the pipes L⁵ L⁶ (Fig. 2) must each be provided with a valve arranged to be unaffected by the flow of steam either way through the pipes L⁵ or L⁶ but operative upon the rise of liquid into the chamber F² to shut the port so that the water cannot get into the steam passages of the apparatus. Such a valve is indicated in Fig. 5 at the mouth of the pipe L⁵ which figure is in effect a portion of Fig. 4 viewed in a plane of section farther from the observer than is the plane of section in Fig. 4. The valve proper is V and its controlling float is V¹.

What I claim as my invention and desire to secure by Letters Patent is:—

1. A gravity feed device for feeding water to a boiler, comprising a feed water connection leading to the boiler, a plurality of float chambers in said connection, valves for alternately admitting water to said float chambers and permitting it to pass from the chambers to the boiler, a main valve casing having a valve therein, a pilot valve casing

having a valve therein, a float in each chamber, actuating connections between the floats and the pilot valve, steam pressure connections leading from the boiler to the pilot valve casing, connections leading from the pilot valve casing to the main valve casing, steam pressure connections leading from the boiler to the main valve casing, an exhaust leading from the main valve casing, and connections leading from the main valve casing to the float chamber, the arrangement being such that when the pilot valve is shifted by the float, the pilot valve will open communications to admit pressure to one side of the main valve and open the other side to exhaust to shift the main valve, which main valve will in turn admit pressure to one of the float chambers and open the other float chamber to the exhaust, substantially as described.

2. A gravity feed device for feeding water to a boiler, comprising a feed water connection leading to the boiler, a plurality of float chambers in said connection, valves for alternately admitting water to said float chambers and permitting it to pass from the chambers to the boiler, a main valve casing having a steam pressure connection leading thereto from the boiler, an exhaust connection leading therefrom, connections leading from said valve casing to the float chambers, a valve in the valve chamber to alternately admit pressure to one float chamber and to open the other to exhaust, a pilot valve chamber, a pilot valve therein, a steam pressure connection leading to the valve casing from the boiler, steam connections leading from the pilot valve casing to the main valve casing to shift the main valve when the pilot valve is shifted, a float in each float chamber, said float chambers and floats therein being so arranged with relation to the boiler that the floats rise above the normal level of the water in the boiler when in their elevated positions, a rock lever connected at each end to one of the floats, and an actuating connection between said pivoted lever and the pilot valve to shift the pilot valve when the lever is shifted by the floats; substantially as described.

3. A gravity feed device for feeding water to a boiler, comprising a feed water connection leading to the boiler, a plurality of float chambers in said connection, valves for alternately admitting water to said float chambers and permitting it to pass from the chambers to the boiler, a main valve casing having a pressure connection leading thereto, an exhaust connection leading therefrom, connections leading from said valve casing to the float chambers, a valve in the valve chamber to alternately admit pressure to one float chamber and to open the other to exhaust, a pilot valve chamber, a pilot valve therein, a pressure connection leading to the

valve casing, connections leading from the pilot valve casing to the main valve casing to shift the main valve when the pilot valve is shifted, a float in each float chamber, and actuating connections between the pilot valve and the floats to shift the pilot valve when the positions of the floats are shifted, and a float controlled valve for stopping the flow of water when the water in the device reaches a predetermined level; substantially as described.

4. A gravity feed device for feeding water to a boiler, comprising a feed water connection leading to the boiler, a plurality of float chambers in said connection, a float in each chamber, valves for alternately admitting water to the float chambers and permitting it to pass from the chambers to the boiler, a main valve casing, a main valve therein, connections leading from the boiler to the main valve casing, connections leading from the main valve casing to the float chambers, an exhaust leading from the main valve casing, the main valve being arranged to be shifted to open communication between the boiler and one of the float chambers and to open the other float chamber to the exhaust, a pilot valve casing, a pilot valve therein, steam pressure connections leading from the boiler to opposite ends of the said pilot valve casing, connections between the main valve casing and the pilot valve casing, said pilot valve being arranged to be shifted to open communication between one of said connections and the pilot valve casing when in one position and to close the connection to the other end of the

main valve when in said position, and actuating connections between the pilot valve and the floats arranged to shift the position of the pilot valve to reverse the steam and exhaust connections for the main valve, substantially as described.

5. An automatic gravity feed device for boiler feed water, comprising a casing having two float chambers therein, a combined water inlet and outlet connection to each float chamber, a float in each chamber, a valve casing above the first mentioned casing and connected thereto, a pilot valve in said casing arranged to reciprocate in a horizontal direction, actuating connections between the floats and the pilot valve, a main slide valve in said casing, connections leading from the float chambers to the valve casing and arranged to be controlled by the main valve to admit pressure alternately to said float chambers and open them to exhaust steam, actuating connections controlled by the pilot valve for actuating the main valve, steam connections controlled by the main valve for alternately admitting pressure to the connections to the float chambers, and steam connections leading to said casing controlled by the pilot valve, the arrangement being such that the pilot valve is shifted by the float which controls the connections for shifting the main valve to admit pressure to one of the float valves and open the other to exhaust, substantially as described.

In testimony whereof I have signed my name to this specification.

WALTER FOWLER.
